AIR VALVE FOR RADIATORS AND THE LIKE

William F. Macdonald, Bridgeport, Conn., assignor to Bridgeport Brass Company, Bridgeport, Conn., a corporation of Connecticut

Application April 8, 1931, Serial No. 528,597

5 Claims. (Cl. 236—61)

This invention relates to improvements in air valves for radiators and the like and more especially to automatic valves for permitting the escape or discharge of air from a steam or similar radiator and preventing the escape of steam or hot vapor therefrom and also preventing the ingress of air into the radiator when the supply of steam or other heating medium thereto is cut off.

10 An object of this invention is the provision of a valve for radiators for heating systems which is provided with a valve-controlled vent to permit the escape or discharge of the air from the radiator when the heating medium is turned on, and 15 which will automatically prevent the escape of the heating medium from the radiator and which will also prevent the ingress of air into the radiator when the supply of the heating medium is cut off.

20 A further object of this invention is the provision of such a valve which is durable, simple in construction, effective in operation and has other advantageous attributes as hereinafter pointed out.

25 To the accomplishment of the foregoing and such other objects as may hereinafter appear, this invention consists in the construction, combination and arrangement of parts hereinafter described and then sought to be defined in the appended claims, reference being had to the accompanying drawing forming a part hereof and which shows, merely for the purpose of illustrative disclosure, a preferred embodiment of my invention, it being expressly understood, however, 30 that various changes may be made in practice within the scope of the claims without digressing from my inventive idea.

In the drawing,—

Figure 1 is a vertical cross sectional view of a 40 complete valve structure constructed according to my invention, illustrated on a slightly enlarged scale.

Figure 2 is a vertical cross sectional view of the discharge end of the valve construction taken 45 along line 2—2 of Figure 1 on a more enlarged scale.

Referring now to the drawing, the numeral 1 designates the casing of the valve construction. The casing is of substantially cylindrical shape, 50 the upper end being of the smallest diameter, the central portion 3 being of a larger diameter, and the lower end 4 being of the greatest diameter. The lower end is internally threaded as at 5 to receive the base member 6 which is provided with 55 a shoulder or boss 7, the side surface of which is

screw threaded as at 8 to fit within, and be secured to, the lower end 4 of the casing or shell 1, which fits within the annular groove 9 formed in the base member 6 adjacent the shoulder or boss 7 so as to form a tight joint therewith. 60

The lower end 4 of the casing or shell is provided at a suitable distance above the base member 6 with a threaded nipple 10 which is adapted to be received in a threaded opening in a radiator, or the like, the lower end 4 of the casing 1 being provided with openings 11 adjacent the nipple 10, whereby air escaping or driven from the radiator by the incoming heating medium will pass into the casing or shell 1. The bent or elbow tube 12 extends loosely through nipple 10, and opening 13 adjacent openings 11 into the casing or shell to drain off water from the casing. The upper end of the top portion 2 is provided with an annular concave shoulder 14 which is formed by bending or rolling the top of the portion 2. 70

Extending from this shoulder 14 is an inwardly directed annular flange 15 which is adapted to receive the upper reduced end 16 of the boss or nipple 17. The parts are adapted to be connected by a friction joint and are driven together to form the construction shown in Figure 2. This boss or nipple 17 provides the valve seat for the valve and is formed with an opening therethrough. A portion 18 of this axial bore is of a relatively small diameter, and connects with the enlarged portion 19 of the bore which tapers to form conical part 20. The shoulder 21 is formed at the junction of the bores 18 and 19, and provides a valve seat for the valve later to be described. The top of the casing or shell 1 is provided with a cap member 22 which is formed at its bottom with the bell-shaped flange 23 and is made so as to fit in and abut concave shoulder 14 and form a relatively tight fit therewith. The parts may be secured by solder or any other suitable means. The cap member 22 is provided with the air vents 24. 80

Returning now to the lower portion of the device, it is to be noted that the top of base member 6 is provided with a further reduced shoulder portion 25 which receives the lower end of the collapsible metal bellows 26 which is permanently mounted thereon. The bellows is formed of thin metal material and is expansible and contractible under the influence of variable pressures, and is sufficiently sensitive so as to respond to small pressure differences. A pin member 27 is positioned within the bellows and is secured to the upper end 28 thereof, and has a reduced upper 95 100 105 110

end 29 which projects through and beyond the end 28 of the bellows. The pin member 27 limits the downward movement of the bellows and also functions to support the hollow float member 5 about to be described.

A cylindrical hollow float member 30, preferably formed of thin metal, is mounted within the casing or shell 1 and between the bellows 26 and the boss or nipple 17. This float member 30 has 10 its lower end closed by a normally inwardly bulged bottom plate 31 which engages the projecting reduced end 29 of the pin 27. A valve stem 32 is secured to the upper end of the float member and has a conically formed extreme portion 33 which forms the valve and which is adapted 15 to engage the valve seat 21 when in closed position. The float member 30 is air tight and preferably contains a small amount of alcohol or other suitable volatile liquid 34.

20 The hollow member is centered and guided in its movement within the casing or shell 1 by means of an annular guide ring 35 which is mounted within the central portion 3 of the casing or shell, and is secured to the inside surface 25 thereof. The annular guide ring 35 is provided with an annular flange 36 to provide an opening 37 of somewhat larger diameter than that of the float member so as to permit the passage of air and steam therebetween.

30 The base member 6 is provided with an opening 38 which leads from the atmosphere to the interior of bellows 26 so as to maintain the interior of the bellows at substantially atmospheric pressure. However, the bellows may be sealed off 35 so that the interior is at atmospheric pressure.

The operation of the device, assuming that the valve is attached to a radiator, which is cold and contains air, and in which steam or other heating medium is to be introduced, is as follows. 40 The incoming heating medium forces air out of the radiator, through the nipple 10, into the casing or shell 1, from which the air escapes through the bore 18 and lateral vents 24 to the atmosphere. When substantially all of the air has been 45 forced from the radiator, the steam or other heating medium enters the casing or shell 1, immediately raising the temperature of the volatile liquid within the float member and the pressure within the float member until that pressure is sufficient to force the normally inwardly bulged bottom plate 31 of the float member downwardly against the reduced end 29 of the pin 27. This 50 downward movement of the bottom plate of the float member is quick or in the form of a snap, and the movement thereof against the end of the pin forces the float member upwardly as a whole and seats the valve 33 against the valve seat 21, thereby preventing the escape of steam from the 55 radiator and the valve casing. When the supply of steam or other heating medium is cut off from the radiator, and the latter, as well as the air valve, cools, and the steam within the shell or casing of the valve condenses, the pressure within the casing is reduced. When this 60 pressure decreases below atmospheric pressure, the bellows 26 will immediately expand and move upwardly, holding the reduced end 29 of the pin 27 against the bottom plate 31, thus holding the valve 33 against seat 21 to prevent the ingress of air into the casing or shell 1 and thence into the radiator. The interior of bellows 26 communicates with the atmosphere by means of the opening 38 in the case member 6. The bellows 26 is made sufficiently sensitive so as to operate on 65 small pressure differences, and when there is a

decrease in pressure in the casing or shell, due to cooling, the bellows immediately responds and expands to maintain the valve 33 on the valve seat 21 and thereby prevent the entry of air into the radiator.

This construction, therefore, provides means for positively preventing the escape of steam while permitting the escape of air and also prevents the ingress of air into the valve and radiator. When the supply of heating fluid is cut off from the radiator, the pressure in the casing or shell 1 gradually lessens, and the pressure within the float member 30 lessens until the normally bulged bottom plate 31 of the float member moves or springs back to its normal position. When the pressure within the casing 1 decreases, the bellows 26 immediately expands and holds the valve 33 positively on the valve seat 21 and prevents the admission of air into the casing. This occurs before bottom plate 31 of float member 30 has moved back to normal position due to the reduction of pressure within the float member. In normal operation, the float member 30 functions thermostatically to control the seating of the valve 33. In addition, if water collects within the casing or shell 1 for any reason, the float member is buoyed up and positively closes the valve to prevent the escape of water therefrom. The pin 27 in addition to engaging the end of the float member, also acts as a stop to engage the base member 6 to prevent the abnormal collapsing of the bellows 26 under maximum pressure.

What I claim is:

1. An air valve for a radiator or the like, including, in combination, a casing adapted to be connected to a radiator, said casing being provided with a vent near its upper end, a hollow float member within the casing provided with a valve at its upper end to close said vent, part of the float member being responsive to pressure changes within said float member, an expandable and contractible bellows within the lower part of the casing having a pin member extending therethrough having engagement with the base of the casing at one end to form a fixed stop, the other end of the pin engaging said float member, whereby when the pressure within the float member increases the valve will be closed, and whereby when the pressure within the casing decreases, the valve will be closed.

2. A device of the character described, including, in combination, a casing adapted to be connected to a radiator, said casing being provided with a vent, a valve for controlling the passage of fluids through said vent, a float member within the casing connected to said valve, said float member having a normally inwardly bulged bottom end movable under changes in pressure within said float member, metallic bellows within the casing provided with means for engaging said bottom end of said float member, said metallic bellows being responsive to pressure changes within the casing, whereby when the pressure within the float member increases, the valve will be closed, and when the pressure within the casing decreases the metallic bellows will expand to cause the float member to move sufficiently to close said valve, said metallic bellows being provided with a pin which limits the collapsing movement of said metallic bellows by contact with the base of the casing.

3. An air valve for a radiator or the like, including, in combination, a casing adapted to be connected to a radiator, said casing being provided with a vent near its upper end, a hollow

float member within the casing provided with a valve at its upper end to close said vent, part of the float member being responsive to the pressure changes within said float member, a plug member secured to the lower end of said casing and provided with an annular shoulder, and an expansible and contractible bellows within the lower part of the casing and mounted on said annular shoulder on said plug member, said bellows having a pin member extending therethrough having engagement with the plug member at one end to form a fixed stop, the other end of the pin engaging said float member, whereby when the pressure within the float member increases, the valve will be closed, and whereby when the pressure within the casing decreases, the valve will be closed.

4. An air valve for a radiator or the like, including, in combination, a casing adapted to be connected to a radiator, the said casing being provided with a vent, a valve for controlling the passage of fluids through said vent, a plug member secured to the lower end of said casing, bellows mounted on said plug member for actuating said valve and extending into said casing, means for limiting the collapsing movement of said bellows, a hollow float member associated with said bellows, and a flanged ring secured to the inside of said casing for guiding said float member while permitting the passage of fluids thereby.

5. A device of the character described, including, in combination, a casing adapted to be connected to a radiator, said casing being provided with a vent near its upper end, a hollow float member within the casing provided with a valve at its upper end to close said vent, part of the float member being responsive to the pressure changes within said float member, a plug member secured to the lower end of said casing and provided with an annular shoulder, an expansible and contractible bellows within the lower part of said casing and mounted on said annular shoulder on said plug member, said plug member having an opening therethrough for permitting communication between the interior of said bellows and the atmosphere, said bellows having a pin member extending therethrough having engagement with the plug member at one end to form a fixed stop, the other end of the pin engaging said float member, whereby when the pressure within the float member increases, the valve will be closed, and whereby when the pressure within the casing decreases, the valve will be closed, and means including a flanged ring secured to the interior surface of said casing for guiding said hollow float member while permitting the passage of fluids thereby.
